FILLER CAP

Andrew Louis Minella, Jr., San Diego, Calif., assignor to Consolidated Vultee Aircraft Corporation, San Diego, Calif., a corporation of Delaware

Application March 8, 1944, Serial No. 525,498

3 Claims. (Cl. 220—40)

1

The invention relates to filler caps for fuel tanks or cells.

In aircraft, it is necessary to provide for quick re-fueling of tanks or cells and to insure against leaks from the loosening of the cap by vibration.

The main object of the invention is to provide an improved filler cap which is easily removable and replaceable for re-fueling, and can be securely locked against loosening by vibration to which the tank and cap are subjected in use.

Another object of the invention is to provide a filler cap which insures safety from leaks and is securely retained in its closed position.

Other objects of the invention will appear from the detailed description.

The invention consists in the several novel features hereinafter set forth and more particularly defined by claims at the conclusion hereof.

In the drawings:

Fig. 1 is a section of a filler cap taken on line 1—1 of Fig. 2, the cover being in its closed position.

Fig. 2 is an inverted plan of the device with the cover locked in its closed position.

Fig. 3 is a section taken on line 3—3 of Fig. 2.

Fig. 4 is an inverted plan of the device with the cover in its released position.

Fig. 5 is a section taken on line 5—5 of Fig. 4.

Fig. 6 is a plan of the gripping member.

Fig. 7 is a perspective viewed from the under side of the plate on the tank which is provided with a seat for the cover.

Fig. 8 is a plan view of the cap on the tank.

Fig. 9 is a perspective of the cover and the depending housing.

Fig. 10 is a perspective of the compression sleeve.

Fig. 11 is a section illustrating a modified form of the invention.

The invention is exemplified on the top of a fuel-tank or cell *a* having a plate *12* which forms a part of the tank and is provided with a filler-opening. This plate is usually formed of sheet metal, and provided with an upwardly offset and upwardly facing annular seat *13* which is curved in cross-section, and an inner downturned flange *14* around the cylindrical filler-opening. The flange *14* is provided with an oppositely disposed pair of helical or inclined cam edges *15* between diametrically opposite depending stop lugs *16* and notches *17*.

The cover or closure *b* for the filler-opening is usually formed of plate metal and comprises a depending or inwardly extending cylindrical rim *18* and a depressed central portion *19* between

which is formed an annular channel in which is confined and secured a gasket *20* of rubber or other suitable composition for engaging the annular seat *13* and forming a leak-proof seal between the cover and said plate. A cylindrical shell *22* has its upper end permanently secured, for example by flash welding or in any other suitable manner, to the cover *b* and houses the locking mechanism and supports said mechanism from the cover.

A gripping or locking member *23* for internally engaging the plate *12* comprises a central disk *23a* and integral radially projecting arms *24*. The disk *23a* slidably fits in the cylindrical housing *22* and arms *24* extend through diametrically opposite longitudinal slots *22a* in the housing *22*. The gripping member *23* is slidable in the housing *22* and arms *24* extend through slots *22a* to connect said member and the housing *22* and cover *b* for conjoint rotation.

The device for shifting the gripping member *23* into operative relation with the plate *12* and forcing the cover into sealed relation with the seat *13* and releasing it for removal comprises, generally, means, comprising a handle, carried by and rotatable relatively to the cover, a spring in the tubular housing *22*, a spring-follower slidably in and rotatable with the housing *22*, and means operable by the handle for shifting the follower and compressing the spring to clamp the plate *12* between the gasket *20* in the cover and the gripping member *23* and releasing the spring and disengaging the gripping member from the plate *12* for the removal of the cover. The handle and said follower-shifting means are also adapted to rotate the cover when the gripping member is released to rotatively position said member for its removal from the tank through the filler-opening and are also adapted by reverse rotation, to slide said member into gripping relation with plate *12* after insertion into the tank.

The rotatable means carried by the cover for compressing and loading the spring for operating the gripping member *23* to engage and release the plate *12* comprises a plate *25* disposed in the central depressed portion of the cover and provided with a downturned rim *26*; a block *27* welded or otherwise suitably secured to the underside of the plate *25*; a bail-like handle *28* which has pinnacles *29* confined by plate *25* in slots *30* formed in the block *27*; a shaft or stem *31*, the upper end of which is riveted to the block *27* and which extends downwardly through the gripping member *23*; and a lever *32* which fits around a polygonal stud *33* on the lower end of stem *31* and is

secured on said stud by a nut 34 which is screw-threaded to the lower end of the stud. The lever 32 comprises oppositely extending radial arms 35. A cotter-pin 36 locks the nut 34 on the stud 33. The plate 25 and block 27 form a head on the stem 31 to which the handle 28 is pivoted. The depressed portion 19 of the central portion of the cover b forms a recess in which the head is disposed and into one side of which the handle can be folded. When the cap is locked on the receptacle, the top of the cover, head and handle are substantially flush so that these parts will all be compactly disposed within the cover. When the handle 28 is swung out of the recess, it provides a firm grip for rotating the gripping mechanism.

The spring-follower comprises a cylindrical or tubular wall 38 which slidably fits in the cylindrical housing 22 and is provided with outwardly extending U-shaped lugs 39 which extend through the slots 22a in the housing 22 and slidably connect the follower and the housing for conjoint rotation. The follower is provided with an integral crosswall 40. The lower end of heavy compression spring 41 is seated on the crosswall 40 and its upper end engages the disk 23a of the gripping member 23 for locking the cover b. The lower end of cylindrical wall 38 is provided with helical or inclined cam edges 43 which are slidably engaged by the lever-arms 35, respectively. Each cam edge 43 is provided at one of its ends with a notch 44 and at its opposite end with a notch 45. Abutments 46 are formed on the cylindrical wall 38 between the notches at the ends of the cam edges 43. Rotation in one direction of the lever 32 through the handle 28 and stem 31 when said arms are seated in notches 44, will slide the follower upwardly in the housing 22 for compressing the spring 41 until the lever-arms 35 are seated in notches 45 and arrested by abutments 46. Reverse rotation of the lever 32 relatively to the follower will lower the follower by means of cam edges 43 and unload the spring 41. The spring 41 has a predetermined expansion so that when the cover and housing are removed from the tank the spring will be unloaded and the gripping member 23 and its arms 24 will be spaced from the cover a sufficient distance to permit the arms to be placed under the annular rim on the plate 12. A relatively light spring 47 is interposed between disk 23a of the gripping member 23 and the cover b and presses the gripping member against the upper end of spring 41 so that when the device is removed from the tank the spring-follower, through spring 41 and member 23, will be pressed downwardly to yieldingly maintain the follower engaged at notches 44 with the lever arms 35. An elastic gasket 48 confined in a centrally recessed portion 49 of the cover, and a washer 50 are interposed between the cover and the block 27 for preventing leakage around the stem 31.

The cover and locking mechanism constitute an assembly which can be unitarily inserted and removed through the filling opening. When the filler device has been removed from the tank, the handle 28 will be turned so that the arms of lever 32 will be rotatively positioned in notches 44, the spring-follower will be in its lowered position, the spring 41 will be unloaded, the gripping member 23 will be separated from the cover, and the spring 47 will press downwardly on gripping member 23 and through the spring 41 press the follower into its assigned engagement with the lever-arms 35.

The inner end of the housing is inserted into the tank through the filler opening with arms 24 of gripping member 23 positioned for insertion under the notches of the flange 14 on the tank plate 12. The assembly is then tilted for angular insertion of the arms 24 into the tank and below plate 12. The device is then in a position to lock the cover by further rotation of the handle 28. The handle is then rotated in the direction indicated by the arrow in Fig. 4. Such rotation of the handle will rotate lever 32, the arms of which are yieldingly held in notches 45, so that the lever will conjointly rotate the spring-follower, housing 22, gripping plate 23, and the cover b until gripping arms 24 strike the abutments 16 on plate 12. The gripping arms 24 will then engage the cam surfaces 15 and prevent the gripping arms and the assembly from being tilted and hold the gasket seated on the plate 12. Abutments 16 will then arrest arms 24 against further rotation in the same direction and prevent further corresponding rotation of the cover b, housing 22 and the spring-follower. The rotation of handle 28 in the same direction will be continued to lock the cover on its seat. Such rotation of the handle will rotate the stem 31 in the cover, housing 22, and the spring-follower and cause the arms 35 of lever 32 to rotate out of notches 44 and slide around the cam edges 43 on the follower until the arms 35 are seated in the notches 45 in the follower. The follower will be shifted upwardly and heavily load and compress the spring 41 which will force the arms 24 of the gripping member 23 into locked relation with the plate 12. The seat 13 and flange 14 of the plate 12 will then be jammed between the internal gripping member 23 and the gasket 20 in the cover against leaks or loosening by vibration. The handle 28, when not in use, can be swung into the recess in the cover.

When the device is locked and is to be removed from filling the tank, the handle 28 is swung out of the recess in the cover and rotated in the direction indicated by the arrow in Fig. 2. The initial rotation of the handle in this direction will rotate the lever 32 relatively to the spring-follower while the plate 12 remains gripped between the cover and arms 24. Lever-arms 35 will be rotated out of notches 45 and around the cam edges 43 until said arms pass into notches 44 at one side of abutments 46. The spring-follower will be lowered and during such lowering movement spring 41 will be unloaded and the cover will be released sufficiently for rotation. The rotation of the handle 28 is continued in the same direction and lever arms 35 engaging abutments 46 at notches 44, will positively rotate the spring-follower, the housing 22, gripping member 23, and the cover b until the gripping arms 24 strike abutments 16 on plate 12 at which time arms 24 will be positioned under the notches 17 in the plate 21 for removal from the tank. The assembly can then be tilted so that arms 24 can be angularly and successively withdrawn through the filler opening. While the device is detached from the tank, the spring 47 will exert pressure on gripping member 23 which, through spring 41, will hold the lower cam-edges of the follower yieldingly in engagement with the lever arms 35. The lever arms 35 will be yieldingly held in notches 44 and the handle 28 and stem 31 will be retained in position for rotation of the device through the filler opening and in readiness for insertion through the filler opening.

In the modification illustrated in Fig. 11, the construction is the same as that previously de-

scribed except that a leaf-spring 51 is substituted for the coil-spring 41. The central portion of the leaf-spring is engaged by the upper end of follower-sleeve 38 and its upwardly bent resilient ends 52 are adapted to engage the arms 37 so that the cap will be operable as previously described.

The invention exemplifies a detachable filler cap which is quickly and easily attachable to and detachable from a fuel tank and which provides 10 a closure which is leak-proof and safely locked against loosening by vibration when used on aircraft.

The invention is not to be understood as restricted to the details set forth, since these may 15 be modified within the scope of the appended claims without departing from the spirit and scope of the invention.

Having thus described the invention, what I claim as new and desire to secure by Letters Pat- 20 ents is:

1. A filler cap assembly for a receptacle having a filler opening and a seat around the opening, comprising a cover for the filler opening carrying a seat-contacting gasket, a tubular housing rigidly secured to the underside of the cover and adapted to extend through said opening, and provided with longitudinal slots, an internal gripping member slidably mounted in the housing and provided with arms extending through said slots and laterally outwardly from the housing, a tubular spring-follower provided with a cross-wall, 25 slideable in the housing, and provided with lugs extending into said slots, cams on the lower end of the tubular follower, a heavy spring in the tubular housing between the gripping member and the crosswall forcing the gripping member toward the cover, a rotatable handle on the outside of the cover, a stem rotatable by the handle, having a lever fixed to the lower end of the stem 30 and engaging said cams for shifting the follower to load the spring, and a light spring in the housing between the cover and the gripping member for urging the gripping member away from the cover and holding the cams in engagement with the lever when the first-named spring is 35 unloaded.

2. A filler cap assembly for a receptacle having a filler opening and a cover seat around the opening, comprising; a cover for the filler opening and adapted to fit on the seat; a tubular housing rigid with the cover and adapted to extend through said opening; an internal gripping member slidably mounted in the housing and provided 40 with arms extending laterally outwardly from the housing; a spring follower slideable in the hous- 50

ing, cams on the follower; a heavy spring in the housing between the gripping member and the follower for forcing the gripping member toward the cover; a rotatable handle on the outside of the cover; a stem rotatable by the handle, having arms rotatable by the stem and engaging said cams for shifting the follower to load the spring, and a light spring in the housing between the cover and the gripping member for urging the gripping member away from the cover and holding the cams in engagement with the arms when the first named spring is unloaded.

3. A filler cap assembly for a receptacle having a filler opening and a cover seat around the opening, comprising; a cover for the filler opening and adapted to fit on the seat; a tubular housing rigid with the cover and adapted to extend through said opening; an internal gripping member slidably mounted in the housing and provided with arms extending laterally outwardly from the housing; a spring follower slideable and non-rotatable in the housing, cams on the follower; a heavy spring in the housing between the gripping member and the follower for forcing the gripping member toward the cover; a rotatable handle on the outside of the cover; a stem rotatable by the handle, having arms rotatable by the stem and engaging said cams for shifting the follower to load the spring, a light spring in the housing between the cover and the gripping member for urging the gripping member away from the cover and holding the cams in engagement with the arms when the first named spring is unloaded; and abutments on the cams, rotatable by the arms for rotating follower, housing and gripping member.
